UNITED STATES PATENT OFFICE

MATHIAS ANTON KOHN, OF MILWAUKEE, WISCONSIN

GARBAGE INCINERATOR

Application filed February 23, 1928. Serial No. 256,319.

This invention relates to garbage incinerators.

Objects of this invention are to provide a novel form of conical hopper or grate which is so constructed that it rests upon lugs carried by the outer casing of the hopper and which permits the passage of the products of combustion from the burner into all portions of the lower surface of the supported garbage, and which consequently permits ready and quick drying of the garbage.

Further objects are to provide a novel form of garbage incinerator in which the burner and the pivotally mounted supply pipe are cast integral, and the burner so constructed that it cannot become clogged or in any way obstructed by the garbage which it supports, but which instead is provided with overhanging portions which shield the fuel or mixture apertures or outlet apertures of the burner.

Further objects are to provide a garbage incinerator in which the conical open work hopper and an annular burner together form a grate, and in which a flat distributor is mounted above the burner so that the entire charge of garbage is heated in a very intimate manner by the products of combustion, and in which an apertured colander is provided for permitting steaming of the garbage during drying, and the outward passage of the steam and vapors from the garbage prior to the burning stage, so that a very quick operating incinerator is produced.

It has been found with incinerators as heretofore constructed that they are sometimes placed upon a wooden floor and consequently scorch or burn the floor. This invention is designed to overcome the defect noted above, and further objects of this invention are to provide a novel form of incinerator which is so constructed that it may be placed directly upon the floor without danger of burning the floor, which is provided with short supporting legs permitting circulation of air beneath the bottom of the incinerator, and which is equipped with lugs which space the ash pan from the bottom of the incinerator, thus giving a double air

space between the hot portions of the incinerator and the floor.

An embodiment of the invention is shown in the accompanying drawings in which:

Figure 1 is a vertical sectional view 55 through the incinerator;

Figure 2 is a transverse sectional view;

Figure 3 is a detail of the rocking arm or lever for dumping the grate.

Referring to the drawings, it will be seen 60 that the incinerator consists of a cylindrical outer shell 1 preferably of wrought iron, which is bolted to a bottom 2 and an upper cover 3. The bottom and the cover are provided with annular flanges, as shown in 65 Figure 1, to facilitate the attaching of the shell 1.

Within this outer shell 1, a perforated colander 4 is positioned and carried by a plurality of lugs 5 secured to the inner side 70 wall of the shell 1. In addition to this, these lugs prevent rotation of the colander, as they pass through notches in the bottom edge. If desired, spacing sleeves 6 may be positioned between the colander 4 and 75 the shell 1 and may carry clamping bolts 7, as shown in Figure 1. The upper portion of the colander is held in correct position by means of a plurality of lugs 8 integral with the upper or top portion 3. 80

The top portion is provided with an outlet or flue opening 9 and with an annular flange surrounding such opening and is provided with a suitable form of removable cover 10 to permit ready dumping of the 85 garbage into the incinerator.

The grate consists of a conical structure formed of a plurality of downwardly and inwardly converging spaced grate bars 11 which are integrally joined to an upper ring 90 12 and a lower ring 13. The upper ring rests upon the top of the lugs 5 and is thus adequately supported at spaced points. The lower ring 13 is positioned around the burner 14 and is spaced therefrom as shown 95 in the drawings.

Above the burner, a flame distributor 15 is provided. The flame distributor is hollow and is provided with a plurality of apertures 16 through which the products 100

of combustion may reach the interior of the mass of garbage. This flame distributor is held in a forwardly and downwardly slanting position by means of a long hook 17 secured with the top 3, as shown in Figure 1.

5 The burner consists of an annular member provided with a plurality of outer apertures 18 and inner apertures 19 for the discharge of the fuel or mixture. The burner 10 is also provided with an overhanging upper annular plate 20 which prevents any garbage from packing against the discharge apertures of the burner. The burner is made integral with a supply pipe 21 and an 15 arm 25 in alignment with the pipe 21, as shown in Figure 3. The supply pipe 21 is preferably provided with an annular groove 22 into which a lug 23 carried by a plate 24 projects and thus prevents axial 20 motion of the pipe, while permitting rocking motion. Preferably, a pair of plates 24 are provided, one being shown in Figure 2, to facilitate the assembling of the device. Preferably, the rod or arm 25 projects through a plate 26 carried by the outer shell 1. This rod or bar is provided with a flattened portion to which the forked end 27 of an operating or tilting handle 28 is pivoted. The handle is provided with 30 a fin 29 which normally fits behind the lip or stop 30, as shown in Figure 3. It is so positioned that the weight of the burner 14, which is offset with reference to the axis of the pipe and rod, urges the fin 29 into 35 engagement with the lug 30. In order to dump the burner or rock it into the dotted line position, all that is necessary is to rock the lever 28 to a slight extent in a counter clockwise direction to free it from the lug 30. Thereafter, the lever is rocked towards 40 the observer, as viewed in Figure 3, and thereafter rocked in a clockwise direction. This permits ready dumping of the ashes and incombustible portion of the charge after 45 burning has been completed.

It is to be noted from Figure 2 that the upper annular plate 20 of the burner is provided with a plurality of radial ribs or fins 31 which aid in spacing the charge upwardly and also aid in securing a free circulation of the products of combustion around all portions of the bottom of the charge. The bottom 2 of the incinerator is provided with a plurality of downwardly 50 extending legs 32 adapted to rest upon a floor or other supporting surface 33 (see Figure 1), and it is to be observed also that this bottom is provided with upwardly projecting lugs 34 upon which an ash pan 35 rests. This ash pan may be provided with a handle 36'. It is spaced from the side wall or shell of the device and also from the bottom, and thus provides a dead air space 36 between the bottom and the ash 65 pan. Further, an air space is provided be-

tween the bottom 2 and the floor 33, so that free circulation of air is permitted, and these parts are thus kept cool. There is thus a double air space between the heated portions of the apparatus and the floor and consequently scorching of the floor cannot occur.

The bottom is provided with a door 37 which may be opened to permit the removal of the ash pan, as required. 75

It will be seen that a novel form of garbage incinerator has been provided in which a very intimate and extensive contact surface is afforded between the heated products of combustion and the charge of garbage, 80 and in which it is impossible to clog the burner by the garbage, however soft and wet it may be.

It will be seen also that the device is so constructed that ready dumping of the incombustible portions of the garbage after 85 firing, may be secured.

Further, it is to be noted that the device is simple in construction and may be readily produced and assembled. 90

Although the invention has been described in considerable detail, such description is intended as illustrative rather than limiting as the invention may be variously embodied and as the scope of such invention is to be 95 determined as claimed.

I claim:

1. A garbage incinerator comprising an outer shell, a perforated colander positioned within and spaced from said outer shell, spaced lugs carried by the shell and having their inner ends extending through notches in the lower end of the colander for supporting said colander within the shell, means for normally spacing the colander from the shell, a conical grate formed with a plurality of inwardly converging slanting bars and having an open central portion, a ring connecting the bars at their upper ends and resting on the lugs which support the colander, a second ring connecting the lower ends of said bars around the open central portion, a tilting burner within said second ring for closing the lower portion of the grate, a plate upon the upper side of the burner with its edges overhanging the same, a plurality of radial ribs upon the upper face of the plate with their upper edges extending above the upper edge of said second ring and a hollow, perforated flame distributor located above said grate. 110

2. A garbage incinerator comprising an outer shell, a perforated colander positioned within and spaced from said outer shell, a plurality of lugs carried by the outer shell and having their inner ends extending through notches in the lower edge of the colander for supporting the colander within the shell, a conical grate formed of a plurality of downwardly converging slanting 125

bars and having an open central portion and an annular upper ring arranged in the colander and supported by said lugs, a tilting burner closing the lower portion of said 5 grate and being of annular construction, a top provided with an outlet opening and a feed door and carried by the upper portion of said shell, a plurality of lugs carried by said top and engaging the upper end of 10 said colander, and a hollow, perforated flame distributor located above said grate.

In testimony that I claim the foregoing I have hereunto set my hand at Milwaukee, in the county of Milwaukee and State of 15 Wisconsin.

MATHIAS ANTON KOHN.
